UNITED STATES PATENT OFFICE.

ALFRED F. McCOLLUM, OF BLOOMSBURG, PENNSYLVANIA, ASSIGNOR TO MAGEE CARPET COMPANY, OF BLOOMSBURG, PENNSYLVANIA, A CORPORATION OF PENNSYLVANIA.

KNIFE-CARRIAGE FOR PILE-CUTTING ATTACHMENTS.

1,322,916.

Specification of Letters Patent. Patented Nov. 25, 1919.

Application filed June 28, 1918. Serial No. 242,474.

To all whom it may concern:

Be it known that I, ALFRED F. McCOLLUM, a citizen of the United States, residing in Bloomsburg, Columbia county, State of Pennsylvania, have invented Knife-Carriages for Pile-Cutting Attachments, of which the following is a specification.

In the operation of the pile cutting mechanism described and claimed in my Patent No. 1,161,710, dated November 23, 1916, I have found that the springs employed to position the auxiliary knife carriage accumulate dirt and lint so that in time they become incapable of proper operation with the result that the knife has a tendency to run out of the groove of the pile wires and frequently break or cause injury. One object of the present invention therefore, is to so construct the auxiliary knife carriage as to make possible the omission of the springs hitherto employed to position it on its supporting studs with a view to increasing the reliability of the attachment as well as to decrease the necessity for inspection and replacement.

Another object of the invention is to so construct certain of the parts of the knife carriage forming part of a pile cutting attachment for a loom that certain portions thereof subjected to wear under operating conditions, may be easily removed and replaced when this is desirable or necessary.

These objects and other advantageous ends I attain as hereinafter set forth, reference being had to the accompanying drawings, in which—

Figures 1 and 2 are respectively side and end elevations of a knife carriage embodying my invention, the latter of these views showing the carriage-supporting bar in section;

Fig. 3 is a vertical section on the line 3—3, Fig. 1;

Fig. 4 is a perspective view of the removable gib forming part of my invention;

Fig. 5 is a side elevation showing a slightly modified form of knife carriage;

Fig. 6 is a vertical section on the line 6—6, Fig. 5;

Fig. 7 is an inverted plan of the auxiliary knife carriage illustrating another feature of the invention; and

Fig. 8 is a perspective view illustrating

the replaceable bearing plate, shown in detail in Fig. 7. 55

In the above drawings 1 represents a bar of rectangular cross section which extends across a loom and has slidably mounted upon it a main knife carriage 2. This includes a body consisting of a bottom member 8 and two side members 9 and 10 held to the bar 1 by two plates 3 and 4 bolted to the inner top portions of said side members so as to rest upon the top surface of the bar 1. The bolts 6 which hold said plates in position extend through vertically elongated openings in the side members so as to permit of their adjustment when it is desired to take up wear between the knife carriage and the bar. 70

Between one of the side members as 10 of the knife carriage and the adjacent side of the supporting bar 1 I mount a gib in the form of an elongated plate 11 of slightly less height than that of the bar 1 and provide it with parallel end extensions 12 designed to fit into correspondingly formed recesses in the opposite ends of said side member so as to be flush with their respective surfaces. The outer face of the side member 9 has connected to it by bolts 13 a plate 7 whereby the rope or cable for moving the knife carriage may be clamped to it, and on the similar face of the side member 10 are two horizontally projecting studs 14 which are preferably tubular and constitute supports or guides for the auxiliary or secondary knife carriage 15. The latter is free to slide on these studs toward and from the main carriage 2 and is provided with a vertically extending guideway for the pile cutting knife 16 which is designed to be forced downwardly by a beveled plate 17 having oppositely extending ends 18 and 19 for engagement with fixed abutments as shown in my above noted patent. 80

When the extension 19 strikes its coacting abutment, said plate is moved away from the upper end of the knife, which is thereupon free to move upwardly in its guides under the action of a spring 20. 90

One of the features of my invention resides in providing the auxiliary carriage 15 with extended bearings 21 for engagement with the studs 14, and the length of 105 these bearings is such that the knife 16 lies

in a vertical plane midway between two other vertical planes, one including the outer ends of said extensions 21 and the other including that face of the auxiliary carriage 5 15 adjacent the main carriage 2. With this arrangement of parts, the engagement of the knife edge 22 with the pile of a fabric to be cut cannot exert a twisting or one-sided stress upon the auxiliary carriage and 10 therefore, does not cause this to press unevenly upon its supporting studs, although in the absence of the elongated bearings or their equivalent, the rearward pressure on the knife causes binding of the carriage on 15 the studs. With the construction shown however, it is free to automatically adjust itself toward and from the main carriage in order to allow the knife to follow the curvature of the pile wire in which it operates 20 without tending to grip the studs 14. The knife carriage may thus move on said studs between the adjacent face of the main carriage 2 and the spring retaining clips or latches 23.

25 If desired, instead of being semi-cylindrical in form as shown in Figs. 1 to 3 inclusive, the bearing extensions may be made tubular as indicated at 24 in Figs. 5 and 6, although in this case they require slots to 30 be formed in their top portions in order that the retaining latches 23 shall not unduly limit the movement of the auxiliary carriage on the studs.

As I have found that under operating 35 conditions there is considerable wear of one of the walls 26 of the groove 25 extending longitudinally in the bottom of the auxiliary knife carriage, I insert a conveniently removable plate 27 in the inner vertical side 40 of said carriage so that its lower portion forms a part of this groove wall 26. As shown in Fig. 7 said wall on one side has three parts, *i. e.*, two inclined end portions and a central part whose surface is substantially parallel to the center line of the 45 carriage. The parts are therefore, so proportioned that the removable plate 27 provides the above noted middle part of the wall and is exposed to the greatest wear 50 under operating conditions.

For properly retaining it in place, the groove or recess in which this plate is mounted is preferably undercut as illustrated and the edges of the plate are correspondingly 55 inclined as shown in Fig. 8. When therefore, under operating conditions, the guiding rib or bar which enters the groove 25 to properly position the knife relatively to the sharpening stones, unduly wears the center part of the wall of said groove, the plate 60 27 which is held in place by a rivet 28, may be conveniently removed and replaced by a new plate of proper dimensions.

Likewise when an objectionable amount

of wear has occurred between the supporting bar 1 and the surfaces provided by the side member 9 and gib 11 of the main knife carriage, said gib, which is preferably made of cast iron, may be conveniently removed and replaced by another having the thickness necessary to take up the wear which has occurred.

Owing to the extended bearings provided on the auxiliary knife carriage, this will freely slide upon the studs 14 toward or 75 from the main knife carriage in permitting the knife to follow the curvature of the pile wires and that without binding upon said studs or requiring any devices such as springs to return it to or maintain it in 80 a mid position on the studs.

I claim:

1. The combination in a pile cutting attachment for looms of a slidably mounted main knife carriage; studs projecting laterally from one side of said carriage; an auxiliary knife carriage slidably mounted on the studs and including extended bearings for the latter projecting beyond its front face; with a knife on the auxiliary carriage having its cutting edge in a plane substantially midway between two vertical planes of which one includes the rear face of the auxiliary carriage and the other includes the outer ends of the extended bearings.

2. The combination in a pile cutting attachment for looms of a slidably mounted main knife carriage; studs projecting laterally from one side of said main carriage; 100 an auxiliary knife carriage slidably mounted on the studs and including substantially semi-cylindrical bearing extensions engaging the lower portions of the studs; a knife on the auxiliary carriage mounted with its cutting edge in a vertical plane substantially midway between the planes of the rear face of the auxiliary knife carriage and of the ends of the bearing extensions respectively; with means adjacent the ends of the studs 110 for normally limiting outward movement of the auxiliary carriage thereon.

3. The combination in a pile cutting attachment for looms of a slidably mounted main knife carriage; studs projecting laterally therefrom; an auxiliary knife carriage slidably mounted on the studs and having a groove in its under side for the reception of positioning means, said groove having a wall including a straight central portion 115 and inclined end portions; with a removable plate mounted on the carriage in position to constitute said central portion of the groove wall.

4. The combination in a pile cutting attachment for looms of a slidably mounted main knife carriage; studs projecting from one side of said carriage; an auxiliary knife

carriage mounted on said studs and free to move into and remain in any given position thereon; bearing extensions for the studs projecting from the outer face of the auxiliary carriage; and a knife mounted on the auxiliary carriage between and to the rear of said bearing extensions with

its cutting edge in a plane midway between two vertical planes respectively including the rear face of the auxiliary carriage and 10 the outer ends of the bearing extensions.

In witness whereof I affix my signature.

ALFRED F. McCOLLUM.
